Des. 189,569
Patented Jan. 10, 1961

189,569

STOVE MAT OR SIMILAR ARTICLE

Joseph C. Breneman, Wooster, Ohio, assignor to Rubbermaid Inc., Wooster, Ohio, a corporation of Ohio

Filed July 28, 1960, Ser. No. 61,560

Term of patent 14 years

(Cl. D9—6)

FIG. 1

FIG. 2

FIG. 3

FIG. 4

Fig. 1 is a plan view of a stove mat embodying my new design.

Fig. 2 is an enlarged fragmentary plan view of one corner thereof.

Fig. 3 is an enlarged fragmentary sectional view as on line 3—3 of Fig. 1.

Fig. 4 is an enlarged fragmentary sectional view on line 4—4 of Fig. 1.

As indicated in Figs. 3 and 4, the under side of the mat is a flat plane.

I claim:

The ornamental design for a stove mat or similar article, substantially as shown and described.
